(57) **CLAIM**

The ornamental design for a wall charger, as shown and described.

DESCRIPTION

FIG. 1 is a front, bottom, right perspective view of a wall charger showing our new design;

FIG. 2 is a rear, top, right perspective view thereof;

FIG. 3 is a front elevation view thereof;

FIG. 4 is a rear elevation view thereof;

FIG. 5 is a top plan view thereof;

FIG. 6 is a bottom view thereof;

FIG. 7 is a left side view thereof; and,

FIG. 8 is a right side view thereof.

The broken lines shown in the drawings illustrate portions of the wall charger that form no part of the claimed design.

A portion of the disclosure of this patent document contains material to which a claim for trademark is made. The trademark owner has no objection to the reproduction of the patent document or the patent disclosure, as it appears in the US. Patent Office records, but reserves all other trademark rights whatsoever.
